PIN CLASP

Lawrence L. Levy, Brooklyn, N. Y.

Application October 16, 1947, Serial No. 780,136

6 Claims. (Cl. 2—323)

1

This invention relates to an improved connector for use between a brassière and a body girdle for holding the brassière and the girdle from shifting on the body of the wearer.

One of the objects of the invention is to provide a clasp with means for clamping a fastener which can be manually forced through the fabric of the girdle, so that a strap attached to the clasp may be effectively used for uniting the girdle to the brassière, without requiring that the clasp itself clamp the material of the girdle.

Another object of the invention is to combine a U-shaped girdle piercing pin or fastener with a clasp having a spring jaw against which the prongs of the fastener or pin are placed, and a lever jaw which is closed against the prongs to clamp them between the two jaws against relative slipping.

Another object of the invention is the provision of a supporting unit, comprising an elastic strap, a buckle member adjustable on the strap and provided with a supporting hook, a clasp having an eye to receive the hook, a U-shaped pin which is insertable through the fabric of the girdle, and means carried by the clasp for clamping the prongs of the pin thereto, so arranged that the points of the pin are entirely concealed and protected.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevation of a brassière and girdle connected by connectors constructed in accordance with the present invention.

Fig. 2 is an enlarged vertical sectional view, taken on line 2—2 of Fig. 1, looking in the direction of the arrows.

Fig. 3 is a sectional view, showing the clasp open.

Fig. 4 is a front elevation of the clasp, showing the pin removed.

Fig. 5 is a rear elevation thereof.

Fig. 6 is a front view of the U-shaped pin.

Fig. 7 is a side elevation thereof.

Fig. 8 is a front view of a modified form of the pin.

Fig. 9 is an edge view of a modified form of the clasp.

Referring to the drawings, which illustrate the practical embodiment of the invention, 10 designates an elastic body girdle, and 11 a conventional brassière. To the bust wings 11^a and 11^b

2

of the brassière the elastic pendant straps 12 and 13 are secured, as by stitching.

The lower end of each strap is provided with a buckle element 14, which is adjustable thereon, and which is constructed with an upturned hook 15.

Connection is established between each strap and the girdle by means of a clasp 16. This clasp includes the back plate 17, which is formed with integral side bearing flanges or bars 18 and 19, located on opposite sides thereof and an open eye 20 at the upper end of the back plate. The back plate is also provided with a pressure jaw 21, which is spaced longitudinally from the eye 20 to provide a pin opening 22, and this jaw is provided with a spring lower portion 21^a, formed by slits 23 at the side edges thereof, and this spring or resilient lower jaw portion is offset inwardly, to a slight degree.

20 A lever jaw 24 is pivotally secured by its integral trunnions 25 and 26 to the integral side bars or flanges 18 and 19, near the lower ends thereof, so that it will swing toward and away from the jaw 21.

25 The lever 24 is formed with a short transverse lever arm 24^a, and a long lever arm 24^b, which extends upwardly along side the jaw 21, and is adapted to completely cover the same.

Girdles are usually made of elastic fabric and it is not practical to form large openings in them, or to pierce them with large teeth in such manner that ripping may result. To provide a coupling means between the clasp and the buckle element 14, a U-shaped wire pin 27, providing parallel prongs 27^a and 27^b, and a connecting cross bar 27^c, is used.

30 The U-shaped wire pin 27 is inserted through the material of the girdle, thus forming insignificant small holes in this material, and then inserted through the pin opening 22 of the clasp 16. The lever jaw 24 is then forced against the prongs of the pin 27, so that they are confined between the jaws 24 and 21, and the points of these prongs concealed from contact with the hands or the garment, and thereby fully protected from injuring any material or the hands of the user.

To insert an effective coupling engagement between the U-shaped pin 27 and the clasp, the pin is formed with a laterally deflected upper end 27^a and laterally deflected prong points 27^b, forming a structure which is slightly vertically curved when looked at edgewise, as in Fig. 7.

When the lever jaw 24 is forced against the prongs of the pin 27, they will be held against slipping out of the clasp, and the material of the girdle will be clamped against the back plate of the clasp, as shown in Fig. 2.

To separate the clasp from the girdle, the lever jaw 24 is opened, and the pin 27 is pulled out of the clasp, when it may be easily removed from the girdle.

To increase the resistance of the pin to slipping, the prongs of the pin may be formed with small knurled teeth 27^d. When the lever jaw 24 is forced to a clamping position, the short lever jaw arm 24^a will engage the prongs of the pin 27, and force these prongs against the resilient jaw portions 24^a, and thereby increase the spring pressure of this jaw upon the prongs of the pin, so that it will be more effectively gripped in the clasp.

To secure the lever jaw 24 against accidental opening movement, a band 28 may be mounted to slide on the back plate 17 and the side flanges 18 and 19 thereof, so that it will restrain the upper end of the lever arm 24^b against opening movement, as shown in Fig. 9.

The clasp may be readily connected and disconnected with the elastic strap, by placing the hook 15 of the buckle element 14 in the eye 20 of the clasp, or by removing the hook from this eye.

The pin clasp may be used on blouses and any type of garment it may be applied to.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An elastic strap having a buckle on its lower end provided with a hook, a clasp having a back plate provided with an eye to detachably engage the hook and a pin opening located below the eye, a U-shaped wire pin having side piercing prongs insertable through the material of a girdle and into said opening, said back plate having side flanges, and a lever to grip said prongs, said lever pivoted to said side flanges and provided with a short lever arm and a long lever arm, said long lever arm concealing the prongs and protecting the points of said pin when in gripping position.

2. An elastic strap having a buckle on its lower end provided with a hook, a clasp having a back plate provided with an eye to detachably engage the hook and a pin opening located below the eye, a U-shaped wire pin having side piercing prongs insertable through the material of a girdle and into said opening, said back plate having side flanges, and a lever to grip said prongs, said lever pivoted to said side flanges and provided with a short lever arm and a long lever arm, said long lever arm concealing the prongs and protecting the points of said pin when in gripping position, the prongs having knurled teeth thereon.

3. An elastic strap having a buckle on its lower end provided with a hook, a clasp having a back plate provided with an eye to detachably engage the hook and a pin opening located below the eye, a U-shaped wire pin having side piercing prongs insertable through the material of a girdle and into said opening, said back plate having side flanges, a lever to grip said prongs, said lever pivoted to said side flanges and provided with a short lever arm and a long lever arm, said long lever arm concealing the prongs and protecting the points of said pin when in gripping position and

a band slidable on the back plate over the long lever arm and adapted to restrain the long arm from opening movement.

4. An article of the class described, comprising an elastic strap for attachment at its top end to a brassière, a buckle having a hook mounted on the lower end of said elastic strap, a U-shaped pin having the free ends of its side arms pointed for insertion through the material of a girdle, a clasp having an eye through which said hook is passed connecting said clasp to said buckle, said clasp being formed with an opening through which said side arms of said pin are passed after being inserted through the material of a girdle, and means on said clasp for gripping the side arms of said pin within said clasp after being passed through said opening.

5. An article of the class described, comprising an elastic strap for attachment at its top end to a brassière, a buckle having a hook mounted on the lower end of said elastic strap, a U-shaped pin having the free ends of its side arms pointed for insertion through the material of a girdle, a clasp having an eye through which said hook is passed connecting said clasp to said buckle, said clasp being formed with an opening through which said side arms of said pin are passed after being inserted through the material of a girdle, and means on said clasp for gripping the side arms of said pin within said clasp after being passed through said opening, said clasp having a back plate formed with said opening, a spring jaw on said back plate below said opening, said gripping means comprising a lever pivotally mounted on said back plate for clamping the side arms of said pin against said plate and engaging said spring jaw to be retained thereby in an operative position clamping said pin against said plate.

6. An article of the class described, comprising an elastic strap for attachment at its top end to a brassière, a buckle having a hook mounted on the lower end of said elastic strap, a U-shaped pin having the free ends of its side arms pointed for insertion through the material of a girdle, a clasp having an eye through which said hook is passed connecting said clasp to said buckle, said clasp being formed with an opening through which said side arms of said pin are passed after being inserted through the material of a girdle, and means on said clasp for gripping the side arms of said pin within said clasp after being passed through said opening, said clasp having a back plate formed with said opening, a spring jaw on said back plate below said opening, said gripping means comprising a lever pivotally mounted on said back plate for clamping the side arms of said pin against said plate and engaging said spring jaw to be retained thereby in an operative position clamping said pin against said plate, said plate being formed with side flanges on opposite sides of said spring jaw and said lever being pivotally mounted between said flanges.
